UNITED STATES PATENT OFFICE

GEORGE K. LEWIS, OF CHICAGO, ILLINOIS, ASSIGNOR TO MET-L-WOOD CORPORATION, OF CHICAGO, ILLINOIS, A CORPORATION OF ILLINOIS

CORNER CONSTRUCTION AND METHOD OF MAKING THE SAME

Application filed March 27, 1929. Serial No. 350,285.

This invention relates to corner constructions and method of making the same.

An object of the invention is to provide a corner construction and method of making the same for use in connection with composite panels made up of laminations of metal and wood and wherein each panel is provided with a veneer or layer of sheet metal, and the body portion cut out to permit bending of the material to form the corner and dispose the metallic veneer within the cut-out portion in such fashion as to render possible a strong and smooth soldered joint.

Another object of the invention is to provide a joint of the character indicated wherein the metallic veneer incorporated in the joint may be either continuous or made up of adjacent end portions disposed in abutting relation, the joint in either case being soldered and presenting a strong and durable construction.

Other and further objects of the invention will more clearly appear from the description and claims hereinafter following.

In the drawings forming a part of the specification, Figure 1 is a fragmentary, perspective view of a panel having portions of the same broken away to more clearly disclose the construction. Figure 2 is a fragmentary vertical sectional view showing the joint and completed corner construction. Figure 3 is a view of a fragment of a panel similar to Figure 1 and disclosing a somewhat different embodiment of the invention. And Figure 4 is a view similar to Figure 2 and illustrating the construction disclosed in Figure 3.

Referring first to Figures 1 and 2, a composite panel is illustrated including a plurality of layers or laminations of plywood forming a body portion 10, these layers being rigidly bonded together by glue in a well-known way. Fixed to the outer surface of the body portion 10 of the panel is a layer, lamination, or veneer of sheet metal indicated at 11, and interposed between the body portion 10 and the veneer 11 is a layer of fabric, such as canton flannel, indicated at 12, glue being interposed between the various layers to effect a permanent bond, the can-

ton flannel having the effect of permitting relative expansion and contraction of the wood and metal without severance of the bond, and also permitting of bending or other manipulation of the panel by reason of this construction. In practicing the method and in order to form the corner construction in the panel, the opposite or inner surface of the body portion is provided with a V-shaped cut-out portion or groove 13 extending along the panel at the point where the corner construction is desired. A layer of fabric 14 is then glued to the inner surface of the body portion so as to extend across the top of the cut-out portion 13. The fabric layer 14 is then provided with a coat of glue and a continuous metallic veneer or layer 15 laid upon the fabric 14 and allowed to become permanently bonded thereto by the drying of the glue. The walls 16 of the cut-out portion 13 are also coated with glue. The layers 14 and 15 are then sawed or cut along the line 16, and the portions 17-17, overhanging the groove, and the portions 18-18 of the fabric layer, are bent into the groove and become fixed in position through the presence of the glue in the groove. The panel is then in position to be bent into the desired corner construction and this may be accomplished by any suitable means, a substantially right angular bend being made in bringing the parts to the position shown in Figure 2, the V-shaped cut-out portion being closed and the portions 17-17 and 18-18 being accommodated in the groove as shown. The joint is completed by the application of solder along the meeting edges of the portions 19-19, as indicated at 20, providing a strong, smooth, inner surface for the construction as well as providing an unmarred exterior surface therefor.

The corner construction thus produced includes the angular walls 21-21 with a continuous outer veneer 22 and a substantially continuous inner veneer 23, the overhanging portions 17-17 and 18-18 respectively, of the metallic veneer and fabric layer being accommodated within the recess 24 provided by the V-shaped portion 13, these portions terminating short of the outer veneer 22.

The fabric interposed between body portion and layers of metal compensates for the different rates of expansion and contraction of the wood and metal and consequently, in addition to facilitating the forming operation, 5 prevents the imposition of unusual strains upon the joint.

Referring now to Figures 3 and 4, the panel construction utilized in practicing the method 10 is substantially the same as that shown in Figure 1 being provided with an outer metallic veneer 30, a fabric layer 31 and a plurality of layers of plywood 32. The V-shaped groove 33 is also provided in substantially the same manner as that heretofore referred to. The method varies from that heretofore described in that the fabric layer 34 upon the inner surface of the panel is made continuous throughout extending into the 15 groove as indicated at 35, glue, of course, being interposed between the adjacent surfaces of the laminations of the plywood and the fabric sheet. The inner veneer 36 is also formed in a continuous layer with a trough 37 pre-formed therein, the veneer 36 with the trough therein, being laid upon the fabric sheet 34 and glue interposed between these members. The panel in this condition is now ready for bending which is accomplished 20 by suitable machinery of any well-known type resulting in the cut-out or groove 35 being closed and the portions of the veneer 36 and fabric 34 incorporated within the groove, as best shown in Figure 4. Solder 25 is then applied along the adjacent inner surfaces of the inner veneer to seal the joint and render the same strong and smooth.

As shown in Figure 4, the article comprises the angular walls 38 and 39 having the outer 30 continuous layer 40 of sheet metal, and the interposed continuous layer of fabric indicated at 41. The body portion of each of the walls 38 and 39 at the corner is provided with the recess 42 provided by the cut-out portion 33, and in the recess are disposed the continuous loops 43 and 44 of the fabric and inner veneer respectively. The soldered joint is indicated at 45.

With respect to both of the above described constructions, it will be understood 40 that they may be used in any situation required and as many of such constructions may be employed as desired. The arrangement has the advantage that a continuous 45 inner veneer for the corner construction is provided and also that an unbroken or unmarred outer metallic surface may be employed. Of course, it will be appreciated that under certain conditions, it might be 50 desirable to omit the outer veneer and the corresponding fabric layer, wherever such a construction might be useful.

While I have herein shown and described 55 what I now consider the preferred manner of carrying out my invention, the same is

merely illustrative and I contemplate all changes and modifications that come within the scope of the claims appended hereto.

I claim:

1. A process of making a corner construction from a member having a fibrous body portion and an exposed metallic veneer permanently bonded thereto, there being a fabric layer interposed between said veneer and body portion, consisting in cutting out the fibrous portion to form a groove therein, cutting the veneer on a line parallel to the groove, folding the adjacent edge portions of the veneer into the groove, bending the body portion to close the cut-out and incorporate the folded edge portions of the metallic veneer and fabric within the cut-out, and applying solder to the crevice provided by the folded edge portions incorporated within the cut-out. 70

2. A corner construction having angularly disposed wall portions, each having a metallic veneer permanently bonded thereto, each veneer having an angular extension extending into the body portion and accommodated within a cut-out in the latter, and a bonding material closing the crevice formed by the meeting edges of said extensions. 90

3. In a corner construction, the combination with angularly disposed walls including a body portion having a cut-out, and provided with a continuous exterior metallic veneer, there being a fabric layer interposed between said veneer, and said body portion, the inner surfaces of said body portion having sheet metal secured thereto, said sheet metal being provided with angular portions incorporated within the cut-out of the body portion and meeting at the edges formed by said angular portions, there being a fabric layer interposed between the sheet metal and angular portions and the inner surfaces of said body portion, and solder flowed along the said meeting edges and joining said meeting edges together. 100

In witness that I claim the foregoing I have hereunto subscribed my name this 23rd day of March, 1929.

GEORGE K. LEWIS.
